UNITED STATES PATENT OFFICE.

EDWARD ALFRED GRAHAM, OF BROCKLEY, ENGLAND; MARIA GRAHAM AND ALFRED GRAHAM EXECUTORS OF SAID EDWARD ALFRED GRAHAM, DECEASED.

COMBINED GRAMOPHONIC AND WIRELESS SOUND-REPRODUCING MEANS.

Application filed May 14, 1924, Serial No. 713,234, and in Great Britain February 1, 1924.

This invention relates to means wherein alternative gramophone and wireless loud speaker reproduction is obtained through a single sound-conduit, horn or acoustic amplifier and has for its object to provide improved sound duct arrangements which will enable either description of sound reproduction to be effectively rendered without it being necessary to remove one or other of the 10 gramophonic or telephonic reproducers or to employ any movable valve device temporarily to isolate either reproducer to prevent sound due to one reproducer proceeding to and setting up vibration in the other 15 reproducer.

To this end, the various sound duct arrangements according to the invention are each characterized by the fact that the duct associated with one reproducer is introduced 20 into the duct associated with the other reproducer in such a manner that the outlet end of the introduced duct is disposed directly in the acoustic path, that is to say, sound waves originated by the first reproducer do not pass an orifice or aperture in the walls of the common duct or acoustic amplifier, but are emitted in a direction parallel with those issuing from the second reproducer.

Further, the outlet end of the introduced duct is substantially of similar cross sectional shape as the part of the duct into which it is introduced and has a free outlet the perimeter walls or edges of which are uniformly separated from the wall of the outer duct by a space which is preferably constant or substantially so. The outlet of the inner duct is, in one form, of circular shape and is mounted in the outer duct which is also 35 of circular cross section in such manner as to be concentric therewith. In other modified forms, the inner duct may have an orifice of rectilinear form. For example, it may be square, and in this case will be 40 mounted within a square duct, or if the inner duct be of elliptical form it will be mounted within an outer conduit of confocal elliptical form.

Whilst an essential feature of the invention is that the outward end of the introduction duct is disposed directly in the acoustic path, so that sound waves originated by the reproducer first in order do not pass an orifice or aperture in the walls of the acoustic

duct, a further constructional feature is that 55 the emission orifice of the inner duct is surrounded on all sides by the outer duct which is of annular or equivalent formation. Various subsidiary features of importance also form part of the present invention as will 60 appear from examples now about to be described with the aid of the accompanying drawings.

In these drawings, Fig. 1 is a part sectional elevation of one arrangement, Fig. 2 being 65 a central vertical section at right angles to Fig. 1 of a portion of the latter. Figs. 3 and 4 are views similar to Fig. 1 of two simple modifications, Fig. 5 is a view similar 70 to Fig. 1 of another arrangement. Fig. 6 is a plan and Fig. 7 a section on the line 7-7 of Fig. 6 of yet another arrangement. Fig. 8 is a similar view to Fig. 7 showing 75 a further modification.

Referring first to Figs. 1 and 2, *a* is a 80 mounting connecting a gramophone tone arm *b* to a trumpet *c*, the said mounting being formed with curved walls *d* constituting an expanded region for the reception of the emission extremity *e* of a sound conduit *f* leading from a loud speaker element *g* so that a gradually developing conduit is maintained from the tone arm *b* to the trumpet *c* 85 accommodating the duct *f* intermediate of the tone arm and trumpet without obstructing the sound waves consequent upon gramophonic reproduction. To still further prevent obstruction of sound waves as referred to, the uppermost or that portion of the introduced duct directly in the path of the sound waves is of conical, tapered or stream line form allowing diversion and free passage of sound waves. Such a device is 90 shown in Figs. 1 and 2 as taking the form of a fin *h*.

Except as to proportions, the arrangement 95 shown in Fig. 3 is practically the same as that shown in Figs. 1 and 2, the principal difference being that the duct *f* is very much shorter. In Fig. 4 the duct *f* in lieu of being at right angles or substantially perpendicular to the axis of the mounting *a* is inclined and curved so as to extend through the top *i* of a cabinet or like article to receive the telephone or loud speaking element *g*.

According to Fig. 5, the gramophone tone 100 are fitted to a mounting such as *a* which has an extension *j* surrounded by the en-

larged portion *k* of a sound duct *f* such as previously referred to the trumpet being attached to the said portion *k* so that in effect the gramophone sound duct may be said to be introduced into the sound duct of the loud speaker, the extension *j* being separated from the portion *k* by an annular concentric aperture space *m*.

In lieu of employing a special mounting, 10 the stationary part of a tone arm, or tone arm mounting, of many existing types may be modified in construction to embody the present invention. Figs. 6 and 7 representing one example wherein the loud speaker 15 duct *f* is accommodated within the mounting *n* of a tone arm *b*, which, in known way, is supported by a bracket or arm *o* so as to be capable only of movement about a vertical axis.

20 A second example is illustrated by Fig. 8 wherein the mounting *n* of a tone arm *b* is supported by a bracket or arm *o* as referred to in connection with Figs. 6 and 7, but in this case the telephone or loud speaker unit 25 *g* is horizontally disposed instead of being placed in a vertical position.

What I claim is:—

1. In means of the kind herein referred to, a sound amplifier, a gramophonic sound 30 duct communicating with said sound amplifier, and a telephonic sound duct extending into said gramophonic sound duct and communicating with said sound amplifier, the outlet end of the introduced sound duct being 35 disposed directly in the acoustic path and at the same time marginally free from and completely out of contact with the wall of the gramophonic sound.
2. In means of the kind herein referred to, 40 a sound amplifier, a gramophonic sound duct communicating with said sound amplifier, and a telephonic sound duct extending laterally through the wall of and into the said gramophonic duct and having its outlet end 45 bent and arranged co-axial with the duct into which it extends, the outlet end of the introduced duct being of the same cross sectional shape as the part of the duct into which it is introduced and having a free

perimeter that is substantially uniformly 50 separated from the latter.

3. In means of the kind herein referred to, a sound amplifier, a gramophonic sound duct communicating with said sound amplifier and a telephonic sound duct extending laterally through the wall of the gramophonic sound duct and having its outlet end portion 55 arranged within such duct and at a distance therefrom such as to form an annular space therewith.

4. In means of the kind herein referred to, a sound amplifier, a gramophonic sound duct communicating with said sound amplifier and a telephonic sound duct extending 60 into said gramophonic sound duct which is made of outwardly expanding form intermediate of its length to accommodate the inlet end portion of the second sound duct, said ducts each having a gradually increasing 65 cross sectional area from its inlet to its outlet, enabling sound reproduction to be effected without obstruction of sound waves.

5. In means of the kind herein referred to, a gramophonic sound duct and a telephonic sound duct extending laterally into the gramophonic duct and having its outlet 70 end arranged co-axial with and out of contact with and directed toward the outlet of said gramophonic duct, the inlet end portion of the telephonic duct, on the side opposite the outlet thereof, being of tapered form to allow of diversion and free passage of 75 gramophonic sound waves past it.

6. In means of the kind referred to, a 80 gramophonic tone arm, a stationary tubular mounting therefor forming part of a sound amplifying conduit and a second sound duct adapted to be provided with a telephonic 85 reproducer, said sound conduit extending through the wall of and into the said tone arm mounting and having its outlet end directed away from said tone arm and arranged to form an annular space with said 90 mounting.

Signed at London, England, this twenty-eighth day of April, 1924.

EDWARD ALFRED GRAHAM.
